Primary Examiner — Jennifer L Rempfer*(74) Attorney, Agent, or Firm* — Wood Herron & Evans LLP(57) **CLAIM**

The ornamental design for a wearable pillow, as shown and described.

DESCRIPTION

FIG. 1 is a front view of a wearable pillow in a flattened state showing the new design;

FIG. 2 is a rear view of the design of FIG. 1;

FIG. 3 is a right side view of the design of FIG. 1;

FIG. 4 is a left side view of the design of FIG. 1;

FIG. 5 is a top view of the design of FIG. 1;

FIG. 6 is a bottom view of the design of FIG. 1;

FIG. 7 is a front view of the wearable pillow design of FIG. 1 in a folded state for wearing on the head and neck;

FIG. 8 is a rear view of the design as shown in FIG. 7;

FIG. 9 is a right side view of the design as shown in FIG. 7;

FIG. 10 is a left side view of the design as shown in FIG. 7;

FIG. 11 is a top view of the design as shown in FIG. 7; and,

FIG. 12 is a bottom view of the design as shown in FIG. 7; and,

FIG. 13 is a front view of the design as shown in FIG. 7, worn by a person.

The broken dash lines shown in the drawing views represent non-claimed subject matter, and neither the lines themselves nor anything within the lines form any part of the claimed invention.

1 Claim, 8 Drawing Sheets(56)
